His Attorney

UNITED STATES PATENT OFFICE.

JOHN B. FREYSINGER, OF NEW BRITAIN, CONNECTICUT.

AUTOMOBILE DOOR LATCH.

Application filed August 5, 1926. Serial No. 127,343.

This invention relates to automobile door latches of the type having a latch or bolt adjacent one side of the door, for instance the inner side, and means on the other side, for instance the outer side, of the door for operating the bolt or latch, there being a clearance space between the bolt and the operating means therefor to accommodate the window glass.

10 The aim of the present invention is to provide a latch of this sort having various features of novelty and advantage.

More particularly, the aim of the invention is to provide an improved connection between 15 the operating means on the outer side of the door and the bolt, this connection being characterized by its simplicity and durability, by its economy in manufacture, the ease and facility with which the parts may be assembled, 20 and by its effectiveness in operation. My improved construction is a rigid one which is well adapted to stand the torsional strains to which it is subjected when the latch is in use, the connection being of particular advantage 25 in that there are no parts rubbing on one another which would result in wear and looseness.

Other objects will be in part obvious and in part pointed out more in detail hereinafter.

30 The invention accordingly consists in the features of construction, combination of elements and arrangement of parts which will be exemplified in the construction hereinafter set forth, and the scope of the application of 35 which will be indicated in the appended claims.

In the accompanying drawings, wherein I have shown, for illustrative purposes, one of the many embodiments which the present invention may take:

Figure 1 is a sectional view taken substantially on line 1—1 of Fig. 2 and shows that portion of the latch attached to the inner side of the door, parts being broken away for the 45 purpose of illustration;

Fig. 2 is a sectional view taken substantially on line 2—2 of Fig. 1;

Fig. 3 is a face view looking at the forward end of the latch;

50 Fig. 4 is a sectional view taken substantially on line 4—4 of Fig. 3 and showing that portion of the connection which is located at the outer side of the door;

Fig. 5 is a perspective view of the connection; and

Fig. 6 is a perspective view of the cross member or portion of the connection.

Referring to the drawings in detail, the door, which is preferably formed of metal, has an outer panel 10, an inner panel 11, and a rail 13. 14 designates, generally, a portion of the door casing having a strike plate or catch 15. Only a portion of the door and its casing are illustrated, as the particular construction thereof forms no specific part of the present invention, it being obvious that my improved latch is applicable to doors of various kinds and shapes. 16 designates the window glass or pane mounted in a guide 17 of any suitable construction, it being understood that the window is adapted to be raised and lowered through the instrumentality of any approved or desired mechanism.

My improved latch includes a latch or bolt of any suitable construction and mounted for movement in any desired manner. By way of example, I have shown the bolt as comprising a slidable sheet metal member 20 having a bolt head 21 riveted thereto and adapted to cooperate in the usual manner with the catch or strike plate 15. This bolt is located to one side of the space provided for the window, in the present instance the bolt being mounted in a casing or support attached to the inner side of the inner panel 11. The support or casing for this bolt may comprise two spaced apart plates 22 and 23 secured together in any suitable manner, as by means of riveting or peening. One of the plates, in the present instance the plate 22, has a slot 24 adapted to receive 90 a lug 25 on the bolt whereby the bolt is suitably guided. The bolt may be normally urged into locking position by means of a spring 26.

Extending through the outer panel 10 is an operating spindle 30 having the usual handle 31. The inner end of the spindle extends into a casing or support of any suitable construction but which is here shown as having a pair of spaced apart plates 32 and 33. These 100 plates have aligned openings or bearings 34. If desired, the plate 32 may be secured to the outer panel 10 of the door, but by way of example, I have shown this plate as forming a parting of a frame which comprises a front or transverse portion 35 and the plate portions 22 and 32. This frame is generally U shape in horizontal section, and the front portion 35 is secured to the rail 13, as by means of screws 35'. The plates 22 and 32 are substantially in 110

parallelism with each other and are on opposite sides of the space in which the window is adapted to slide up and down, as shown most clearly in Fig. 2. The front portion 35 has an opening 36 for accommodating the bolt head and also has an opening 37 for accommodating my improved connection which is about to be described. The rail 13 is bowed out as at 13' so as to accommodate the protruding portion of the connection.

Referring now more particularly to my improved connection between the operating means or spindle 30 and the bolt, 40 designates an arm fixed to, so as to rotate with, the spindle 30; 41 is a second arm journalled in the frame comprising the plates 22 and 23; and 42 is a cross portion rigidly connecting the arms together. The arm 41 is operatively connected to the bolt in any suitable manner, in the present illustrative disclosure this arm being in the form of a roll-back which bears against an extension 44 on the bolt so that, when the roll-back is turned counterclockwise (referring to Fig. 1), the bolt will be retracted. The roll-back 41 may have a lug 45 adapted to engage against the end wall 46 of the inner casing so as to limit the extent of rotary movement of the connection in a clockwise direction. If desired, the parts 40, 41 and 42 may be made all of one piece or casting, but, by preference, they are made as illustrated to effect economy in manufacture and simplicity in assembly. As shown, the connecting portion 42 has a flange 47 at each end adapted to be respectively riveted or bolted to the arms 40 and 41. The arm 40 is secured to the spindle so as to rotate therewith by means of a bushing or hub 48, this bushing being polygonal and having a driving fit in a similarly shaped opening in the arm. The ends of the bushing are round, as illustrated, so that they may be journalled in the openings 34, and the bushing has a square opening which receives the squared end of the spindle. The other arm 41 is fixed to a similar hub or bushing 49 which is journalled in the side plates 22 and 23 of the inner casing. The arm 40 may have an outturned lug or projection 50 against which bears the end of a spring 51 whereby the connection is normally urged to the position shown in Figs. 1 and 4.

It will be noted that the axes of the bushings 48 and 49 are alined so that the arms swing about a common axis. The bushings are to opposite sides of the space provided for the window, and the connection extends forwardly and through the opening 37 in the front plate of the lock frame. The construction is such that the window guide may extend close up to the selvage of the latch so that a window pane of maximum size may be used. In the present illustrative disclosure, the cross portion 42 of the connection in no position of adjustment extends rearward-

ly beyond the selvage; that is to say, rearwardly beyond the inner face of the front plate 35. The forward face 52 of the cross member 42 is preferably curved about the axis of the connection as a center. The rear side of the connection has two faces which are at such an angle to one another that, when the connection is in the normal or inoperative position shown by full lines in Figs. 1 and 4, one of the faces 53 is alined with the inner face of the front plate 35, and, when the connection is in the operated position shown by dotted lines Fig. 4, the other face 54 is substantially alined with the front plate 35. With this construction, a very strong and rigid connection is obtained while, at the same time, the guide 17 of the window may be brought close up against the selvage of the latch.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense. Quite obviously, the lock may be provided with a latch on the inner side of the door for preventing operation of the bolt, and may be provided with a supplemental key controlled mechanism on the outside of the door, and may further be provided with a lever or the like for operating the bolt from the inside of the door, but as these various arrangements are old and well-known in the art, they are not illustrated in the drawings.

It is also to be understood that the language used in the following claims is intended to cover all of the generic and specific features of the invention herein described and all statements of the scope of the invention which, as a matter of language, might be said to fall therebetween.

I claim as my invention:

1. A latch of the character described having a pair of spaced apart supports with a free space between them for accommodating a window, a bolt carried by one of said supports, operating means carried by the other of said supports, and a rigid element between said operating means and bolt, said element including an arm pivoted in one of said supports and connected to said operating means, an arm pivoted in the other of said supports in alinement with said first arm and operatively associated with said bolt, and a cross member rigidly connecting said arms together and positioned forwardly of the line on which said arms are pivoted and forwardly of said window space.

2. A latch of the character described having a pair of spaced apart supports with a free space between them for accommodating a window, a bolt mounted in one of said sup-

ports, operating means mounted in the other of said supports, a pivoted arm in one of said supports and connected to said operating means, a roll-back journalled in the other of said supports on an axis coincident with said first arm and cooperating with said bolt, and a rigid connection between the forward ends of said arms.

3. A latch of the character described having a pair of spaced apart supports with a free space between them for accommodating a window, a front plate connecting the forward ends of said supports and having an opening, a bolt carried by one of said supports, an operating spindle extending into the other of said supports, an arm journalled in said last mentioned support and receiving said spindle, an arm constituting a roll-back journalled in the other of said supports and operatively associated with said bolt, said arms being journalled in alinement with one another and the forward ends of said arms extending through said opening in said front plate, and a rigid connection between the forward ends of said arms and arranged not to extend rearwardly of said front plate in any position of said connection.

4. A latch of the character described having a pair of spaced apart supports with a free space between them for accommodating a window, a bolt slidably mounted in one of said supports, an operating spindle extending into the other of said supports, and a rigid element through which said spindle effects operation of said bolt, said element comprising an arm journalled in the last mentioned support and receiving said spindle, an arm journalled in the other of said supports on a line with said first arm and operatively associated with said bolt, said arms extending forwardly of the free space provided for said window, and a rigid cross portion between the forward ends of said arms, said cross portion having its rear side provided with two faces at an angle to each other and so arranged that when the element is in inoperative position one of said faces is in a vertical plane and when the element is in operated position the other of said faces is in the same vertical plane.

5. A latch of the character described having a pair of spaced apart supports with a free space between them for accommodating a window, a connecting plate at the forward ends of said supports and having an opening, a bolt slidably mounted in one of said supports, an operating spindle extending into the other of said supports, and a rigid element for associating said operating spindle with said bolt, said element including an arm journalled in said last mentioned support and receiving said spindle, a roll-back journalled in the other support on a line with said arm and operatively associated with said plate, said arm and roll-back extending forwardly through said front plate, and a cross member rigidly connected to said arm and roll-back and having its rear side provided with two faces at an angle to one another and so located that when the element is in inoperative position one of said faces is in substantial alinement with said front plate and when the element is in operated position the other face is in substantial alinement with said front plate.
